ABSTRACT

A log turning assembly for rotating logs to be fed to a grinder magazine by a predetermined angle. The assembly comprises a conveyor for carrying the logs above the grinder magazine and a swivel box rotatably supported on a structure above the grinder magazine. First gate means are located on the conveyor for dropping the logs in the swivel box, means are provided for turning the box by the predetermined angle when loading with logs, and a second gate means are located at the bottom of the swivel box for dropping the logs in the grinder magazine after rotation of the swivel box.

LOG TURNING ASSEMBLY

This invention relates to a log turning assembly for rotating logs to be fed to a grinder magazine by a predetermined angle.

During installation of grinders in a pulp processing plant, it often happens that the space available for installing the grinders requires that such grinders be positioned so that the magazines are oriented at such an angle that the logs fed to such magazines, on conveyors are not in the right direction. Of course, the conveyors could be rearranged but this often disturbs the whole processing plant. Consequently, it is less expensive to provide log turning assemblies for turning the logs when they are unloaded from the conveyors.

It is therefore the object of the invention to provide a log turning assembly which is very simple and inexpensive.

The log turning assembly in accordance with the invention comprises a swivel box rotatably supported on a structure above the grinder magazine and below the conveyor. First gate means are located on the conveyor for dropping the logs in the swivel box and means are provided for turning the box by the angle required when loaded with logs. Finally, gate means are located at the bottom of the swivel box for dropping the logs in the grinder magazine after rotation of the swivel box.

The structure supporting the swivel box includes a track and the box is provided with rollers for rotation on the track so as to permit the angle of movement of the box. The means for turning the box may include a pinion rotatably mounted on the structure, a chain secured to the box and adapted to mesh with the pinion, a rack also meshed with the pinion, and means for operating the rack to cause the rotation of the pinion and the angular movement of the box.

The gates are opened and closed and the swivel box may be rotated by means of air pressure cylinders. Such air pressure cylinders are controlled by an electric circuit so as to sequentially open the first gate means to load logs in the swivel box, close the first gate means when the level of the logs in the swivel box has reached a predetermined height, turn the swivel box after the first gate means are closed, open the second gate means when the swivel box has reached its unloading position, close the second gate means when the swivel box is empty, and return the swivel box to its loading position when the second gate means are closed. The above operations may be done manually or automatically.

The invention will now be disclosed with reference to a preferred embodiment thereof and to the accompanying drawings in which:

FIG. 1 illustrates a perspective view of the log turning assembly in accordance with the invention;

FIG. 2 illustrates a side view of the log turning assembly of FIG. 1;

FIG. 3 illustrates a top view of the swivel box supporting structure;

FIGS. 4 and 5 illustrate the rotation of the swivel box by an angle of 90°; and

FIGS. 6 and 7 illustrate the electric circuit controlling the operation of the log turning assembly.

Referring to FIGS. 1 to 3, there is shown a portion of a conveyor including two gates 10 positioned between two end rollers 12 of conveyor belts 14. The gates are rotatably supported on the conveyor by shafts 16 and

2

are operated by air pressure cylinder 18 secured to the conveyor and having a piston 20 secured to a lever 22 keyed on one of the shafts 16. The two gates are operated together by means of a lever 24 which is coupled to lever 22 and to another lever 26 keyed to the other shaft 16. A limit switch LS₁ is located adjacent one end of lever 24 so as to be actuated when the gates 10 are closed.

A structure is provided for supporting a swivel box 30 positioned right underneath gates 10. Such structure is composed of four columns 32 each having angle brackets 34 supporting a track 36. The swivel box 30 has rollers 38 mounted on each corner thereof and adapted to roll on track 36. The swivel box is rotated by means of a pinion 43 rotatably mounted on a transverse bar 42 located between two columns 32 and having a first gear meshing with a chain 44 secured to an arcuate bar 46 attached to swivel box 30. A second gear is provided on the pinion 47 and meshes with a rack 48 slidably mounted on transverse bar 42. The rack 48 is operated by an air pressure cylinder 50 secured to rack 48. Limit switches LS₂ and LS₃ are provided for detecting that the swivel box is in its loading and unloading position respectively. A photocell PC₁ (not shown in FIG. 1-3) is also provided for detecting the presence of wood in the swivel box whereas photocells PC₂ and PC₃ are provided for detecting that the swivel box is full and half full respectively.

Two gates 56 are located at the bottom of the swivel box. Each gate is rotatably mounted on a shaft 58 and operated by an air pressure cylinder 60 having its piston 62 secured to a lever 64 keyed to shaft 58. Limit switches LS₄ and LS₅ are provided for detecting that the gates 56 are closed. As illustrated in FIGS. 4 and 5, gates 56 are closed during rotation of the swivel box. The gates 56 are opened after rotation of the swivel box to unload the logs onto the grinder magazines not shown located right underneath the swivel box.

Referring now to FIGS. 6 and 7, there is shown the electrical circuit for operating the log turning assembly disclosed above. A suitable source of power such as 115 V, 60 Hz is applied to lines L₁ and L₂ through manual switch SW₁ and fuse F. When switch SW₁ is closed, a pilot light PL₁ will light up to indicate that the circuit is on. If the swivel box is empty, as should normally be the case, the photoelectric cell PC₁ normally located at the bottom of the swivel box will detect the absence of logs and energize a second pilot light PL₂ indicating that the swivel box is empty. A reset button RS is also provided for permitting to continue the cycle of operation of the machine following a loss of power or the opening of switch SW₁. The operation of push button RS energizes relay RST and such relay will close contacts RST-1 to lock itself and contacts RST-2 to power the circuit.

The operation of the log turning apparatus may be manual or automatic. If the operator desires to operate the apparatus manually, the switch SW₂ is turned to the position MAN. If it is desired to operate the apparatus automatically the switch SW₂ is turned to position AUTO.

In the position MAN, the gates 10 are opened to permit logs to fall onto the box by pressing button OP. If the limit switch LS₂ is closed indicating that the swivel box is in its loading position and if limit switches LS₄ and LS₅ are also closed indicating that both gates 56 of

the swivel box are closed, a solenoid OPN will be energized through normally closed contacts R2-1 and T1-1. As it will be seen later, relay R₂ operating contacts R2-1 is energized when the closed button CL is operated or when the swivel box is full. The contacts T1-1 are operated by timing relay T₁ after a predetermined time interval to prevent the operator from mistakenly reopening the gates before turning the swivel box to its unloading position as it will be seen later. Solenoid OPN controls the cylinder 18 which operates the gates 10.

The pressing of button OP also energizes relay R₁ and timing relay T₁. Relay R₁ and timing relay T₁ lock themselves through contacts R1-1 of relay R₁ and normally closed contacts R4-1 of a relay R₄ which opens its contacts only when the swivel box is rotated to its unloading position as it will be disclosed later. Following opening of the gates 10, the box will be loading with logs.

When the box is full, the operator presses on closed button CL to energize a solenoid CLS controlling the operation of the cylinder 18 for closing the gates 10. The pressing of button CL also operates pilot light PL₃ to indicate that the box is full and relay R₂ to open contacts R2-1 so as to deenergize solenoid OPN. It will also be noted that the relay R₂ is also energized by photocells PC₂ and PC₃ when the swivel box is full.

When the gates 10 are closed, the operator may press a button ROT to operate solenoid ROTT through normally open contacts R3-1 of relay R₃. Relay R₃ is closed when the gates 10 are closed thereby operating limit switch LS₁. The energization of solenoid ROTT controls the operation of cylinder 50 to rotate the swivel box 30.

The swivel box is then in its unloading position and a relay R₄ is operated by the closure of limit switch LS₃ which, as mentioned previously, is operated when the swivel box is in its unloading position. The unloading of the logs may be done by pressing buttons LF when only the left hand gate 56 is open, RG when only the right hand gate 56 is open or button BT when both gates 56 are open. The manual operation of the gates 56 will not be disclosed now because it is identical to the automatic operation of the log turning assembly.

When it is desired to return the swivel box to its loading position after unloading of the logs, the return button RET is pressed by the operator for energizing solenoid RETN which controls cylinder 50.

If the operator chooses to operate the apparatus automatically, switch SW₂ is moved to position AUTO. The automatic opening of the gates will be initiated by the pressing of button LD instead of button OP. Solenoid OPN and relays R₁ and T₁ are thus operated in the same manner as for the manual operation. A timing relay T₂ is provided for permitting the swivel box 30 to fill to its full capacity. Such timing relay T₂ is energized through normally closed contacts R3-2 of a relay R₈ which is deenergized when the gates 10 are open because limit switch LS₁ is open. When the timing period of relay T₂ has lapsed, contacts T2-2 are closed to cause energization of solenoid CLS to close the gates 10 if the level of the logs in the swivel box has exceeded the half full mark controlled by photocell PC₃. The light PL₃ and the relay R₂ will also be energized. The energization of relay R₂ will close contacts R2-1 to release solenoid OPN. It will also be noted that the solenoid CLS, the pilot light PL₃ and the relay R₂ may also

be operated by photocell PC₂ when the swivel box becomes full before the end of the timing period of timing relay T₂.

The energization of relay R₂ also closes contacts R2-2 to energize relay R₅ to normally close contacts R4-2 of relay R₄. As it will be seen later, relay R₄ is not energized until the swivel box 30 has moved to its unloading position. Relay R₅ locks itself operated through its own contacts R5-1 and energizes timing relay T₃ through its other contacts R5-2. After a predetermined timing interval, timing relay T₃ closes its contacts T3-1 to energize solenoid ROTT to rotate the swivel box 30. The timing period of timing relay T₃ is chosen so as to insure that the gates 10 will be closed before the swivel box 30 starts to rotate.

The unloading of the box is initiated by the operator in the manual and automatic operation of the apparatus. To open the left hand gate, button LF is closed to energize relay R₆ through now closed contacts R4-4 of relay R₄. As mentioned previously, relay R₄ is energized through limit switch LS₃ when the swivel box has moved to its unloading position. The energization of relay R₆ closes contacts R6-1 to operate timing relay T₆ and relay R₁₀. The timing relay T₆ and the relay R₁₀ lock themselves through their own contacts T6-1 and R10-1 connected in series. The operation of relay R₁₀ closes contacts R10-2 to energize solenoid HDLF which releases the pressure on the cylinder 60 controlling the operation of left gate 56. The closure of contacts R10-2 also energizes relay R₁₂ through normally closed contacts R6-2 of timing relay T₆.

The energization of relay R₁₂ closes contacts R12-1 to operate solenoid OPLT controlling the operation of cylinder 60 to open left gate 56. The timing period of timing relay T₆ is adjusted so that its contacts T6-1 and T6-2 are operated shortly after solenoid HDLF and OPLT are energized so as to impart a high pressure on the cylinders at the beginning of the opening of the gates only. There is no pressure applied on the cylinders towards the end of the opening of the gates so as to prevent slamming of the gates at the end of their travel.

When the operator releases the button LF, relay R₆ is released and timing relay T₇ and relay R₁₁ will be energized through then closed contacts T6-3, normally closed contacts R9-1, normally closed contacts R6-2 and normally closed contacts R7-1. The function of relays R₇ and R₉ will be disclosed later. The timing relay T₇ and relay R₁₁ lock themselves operated through normally closed contacts T7-1 and then closed contacts R11-1. The energization of relay R₁₁ also closes contacts R11-2 to energize solenoid CLLf to close the left gate 56. After the expiration of the timing period of timing relay T₇, contacts T7-2 will be opened to release relay R₁₀ and timing relay T₆ so as to reset such relays. The contacts T7-1 of timing relay T₇ will also be opened to release relay R₁₁ and timing relay T₇. The three solenoids are then released and the whole pressure is applied on the left gate cylinder to hold the gate closed.

When the operator wishes to open the right gate 56, the button RG is pushed to close the circuit of relay R₈. The operation of relay R₈ closes contacts R8-1 to energize timing relay T₈ and relay R₁₃. The timing relay T₈ and the relay R₁₃ lock themselves operated through their own contacts T8-1 and R13-1 connected in series. Relay R₁₃ closes contacts R13-2 to energize sole-

noid HDRG which releases the pressure on the cylinder 60 controlling the operation of the right gate 56. The closure of contacts R13-2 also energizes relay R₁₅ through normally closed contacts T8-2 of timing relay T₈. The energization of relay R₁₅ closes contacts R15-1 to operate solenoid OPRG controlling the operation of cylinder 60 to open right gate 56. The timing period of timing relay T₈ is adjusted so that its contacts T8-1 and T8-2 are operated shortly after the solenoids HDRG and OPRG are energized so as to impart a high pressure on the cylinders at the beginning of the opening of the gates only. There is no pressure on the cylinders at the end of the opening of the gates so as to prevent slamming of gates.

When the operator releases the button RG when the swivel box is empty, relay R₈ is deenergized to close contacts R8-2 and timing relay T₉ and relay R₁₄ will be energized through then closed contacts T8-3 and normally closed contacts R9-2 and R7-2. The timing relay T₉ and relay 14 lock themselves operated through their contacts T9-1 and R14-1. The operation of relay R₁₄ closes contacts R14-2 to energize solenoid CLRG to close right hand gate 56. After the expiration of the timing period of timing relay T₉, contacts T9-2 will be opened to release relay R₁₃ and timing relay T₈ so as to reset such relays. The contacts T9-1 of timing relay T₉ will open to release relay R₁₄ after a predetermined timing period to release itself and relay R₁₄. The three solenoids are then released and the whole pressure is re-applied on the cylinder controlling the right gate to hold the gate closed.

When the operator desires to operate both gates at the same time, he pushes button BT to energize relay R₇. The energization of relay R₇ closes contacts R7-3 and R7-4 to initiate the opening of both gates together. When push button BT is released, relay R₇ is released to close both gates in the manner disclosed above for the left and right gates.

The automatic opening and closing of gates 56 is initiated by timing relay T₄ and relay R₉ which are energized through normally closed contacts T5-2 of timing relay T₅, switch SW₃ which is closed when the swivel box is loaded and through contacts R4-3 of relay R₄ which is operated when the swivel box 30 is in its unloading position. After its timing period has elapsed (time necessary to stop the swivel box at its unloading position) relay T₄ closes its contacts T4-1 and T4-2 to initiate opening of both gates 56 in the same manner as disclosed above. When the timing period of timing relay T₅ has ended, contacts T5-2 open to release timing relay T₄ and relay R₉ and thus close the gates and bring the circuit back to its rest position.

Relay R₉ is used to prevent the gates 56 from closing when contacts T6-3 are closed until the timing period of T₅ has ended.

Contacts R7-1 and R7-2 which are positioned in the energizing circuit of timing relay T₇ and relay R₁₁ on one hand and timing relay T₉ and relay R₁₄ on the other hand are provided to maintain the left or right gate 56 opened if the operator, after having pressed button LF or button RG decides to open both gates by pressing button BT even if he releases buttons LF and RG. Contacts R7-1 or R7-2 will then open to prevent energization of the relays associated with the closure of the gates 56.

After the timing period of timing relay T₅ has elapsed, contacts T5-1 are closed and solenoid RETN

is energized to control the operation of cylinder 50 which brings the swivel box back to its loading position.

Although the invention has been disclosed with reference to a preferred embodiment thereof, it is to be understood that various modifications may be made thereto and that the scope of the invention is to be limited by the claims only.

I claim:

- 10 1. A log turning assembly for rotating logs to be fed into a grinder magazine by a predetermined angle comprising:
  - a conveyor for carrying the logs above the grinder magazine;
  - b. a swivel box rotatably supported on a structure above the grinder magazine and below said conveyor;
  - c. first gate means located in said conveyor for dropping logs in said swivel box;
  - d. means for turning the box by said predetermined angle when loaded with logs; and
  - e. second gate means located at the bottom of said swivel box for dropping the logs in the grinder magazine after rotation of the swivel box.
- 20 2. A log turning assembly as defined in claim 1, including air pressure cylinders for opening and closing the first and second gates.
- 30 3. A log turning assembly as defined in claim 1, wherein said structure includes an annular track and wherein rollers are mounted on said box for rotation on said track so as to permit angular movement of said box by said predetermined angle.
- 35 4. A log turning assembly as defined in claim 2, wherein the means for turning the box include a pinion rotatably mounted on said structure, a chain secured to said box and adapted to mesh with said pinion, a rack also meshing with said pinion, and means for operating said rack to cause rotation of the pinion and the angular movement of the box.
- 40 5. A log turning assembly as defined in claim 4, wherein said means for operating said rack is an air pressure cylinder.
- 45 6. A log turning assembly as defined in claim 5, further comprising an electric circuit for controlling the operation of said air pressure cylinders so as to sequentially operate the first gate means to load logs in the swivel box, close the first gate means when the level of the logs in the swivel box has reached a predetermined height, turn the swivel box after the first gate means are closed, open the second gate means when the swivel box has reached its unloading position, close said second gate means when the swivel box is empty, and return the swivel box to its loading position when the second gate means are closed.
- 50 7. A log turning assembly as defined in claim 6, wherein said electric circuit includes solenoids for operating said cylinders and wherein the sequential operation of said solenoids is controlled manually.
- 55 8. A log turning assembly as defined in claim 7, wherein a limit switch is provided for preventing rotation of the swivel box before the first gate means are closed.
- 60 9. A log turning assembly as defined in claim 7, wherein timing relays are provided for controlling the time necessary for opening and closing the second gate means.

10. A log turning assembly as defined in claim 9, wherein said second gate means includes two separate gates which may be operated separately or together.

11. A log turning assembly as defined in claim 7, wherein a timing relay is provided for preventing re-opening of said first gate means before the swivel box has gone to its unloading position.

12. A log turning assembly as defined in claim 6,

wherein said electric circuit includes solenoids for operating said cylinders, and wherein the sequential operation is controlled automatically.

13. A log turning assembly as defined in claim 12, wherein limit switches, photocells and timing relays are provided for controlling the sequential operation.
